UNITED STATES PATENT OFFICE

JOHN R. REPLOGLE, OF DETROIT, MICHIGAN, ASSIGNOR TO COPELAND PRODUCTS, INC.,
OF MOUNT CLEMENS, MICHIGAN, A CORPORATION OF MICHIGAN

DESIGN FOR A REFRIGERATOR TOP

Application filed June 24, 1932. Serial No. 44,185. Term of patent 7 years.

To all whom it may concern:

Be it known that I, JOHN R. REPLOGLE, a citizen of the United States, residing at Detroit, in the county of Wayne and State of Michigan, have invented a new, original, and ornamental Design for Refrigerator Top, of which the following is a specification, reference being had to the accompanying drawing, forming part thereof.

In the drawing:

Fig. 2 is a fragmentary cross-sectional view thereof, taken along line 2—2 of Fig. 1.

What I claim is:

The ornamental design for a refrigerator top, as shown.

JOHN R. REPLOGLE.
